UNITED STATES PATENT OFFICE.

JOHN THOMAS LISTER, OF CLEVELAND, OHIO.

DESIGN FOR AN INCANDESCENT-LAMP BULB.

SPECIFICATION forming part of Design No. 27,267, dated June 29, 1897.

Application filed May 1, 1897. Serial No. 634,779. Term of patent 14 years.

To all whom it may concern:

Be it known that I, JOHN THOMAS LISTER, a citizen of the United States, and a resident of Cleveland, county of Cuyahoga, State of Ohio, have invented certain new and useful Improvements in a Design for Incandescent Bulbs, of which I hereby declare the following to be a full, clear, and exact description, such as will enable others skilled in the art to o which it appertains to make and use the same.

My invention relates to improvements in a design for incandescent bulbs or shells, of which the following is a specification, reference being had to the accompanying drawings, 5 showing a part thereof.

Figure 1 is a longitudinal view of the invention, showing both extremities. Fig. 2 shows an end view.

The leading feature of my design consists o in a flattened bulb-like extension from the main portion of the shell of the lamp, which

is rounded at the extremity in the arc of a circle. The outline of the bulb-like extremity is withdrawn toward the center, where it meets the curve of the shell, thus partially 25 separating the shell and bulb.

As shown in the drawings, 1 is the shell; 2, the rounded extremity of the shell; 3, the narrowed connection with the flattened bulb. 4 is the curved edge of the bulb. 30

The outlines are smooth, as shown.

The bulb is completed by a curved but flattened surface which closes the extremity of the bulb.

What I claim is—

A design for an incandescent bulb, substantially as set forth.

JOHN THOMAS LISTER.
